No. 727,380.

PATENTED MAY 5, 1903.

R. G. KIRKWOOD.
LIQUID FUEL BURNER.
APPLICATION FILED OCT. 14, 1901.

NO MODEL.

UNITED STATES PATENT OFFICE.

ROBERT G. KIRKWOOD, OF PITTSBURG, PENNSYLVANIA.

LIQUID-FUEL BURNER.

SPECIFICATION forming part of Letters Patent No. 727,380, dated May 5, 1903.

Application filed October 14, 1901. Serial No. 78,629. (No model.)

To all whom it may concern:

Be it known that I, ROBERT G. KIRKWOOD, a citizen of the United States, residing at 23 Alpha Terrace, Pittsburg, in the county of Allegheny and State of Pennsylvania, have invented certain new and useful Improvements in Liquid-Fuel Burners; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 My said invention relates to liquid-fuel burners.

The object of my invention is the production of a device for preparing petroleum or other oils as fuel for steam-boilers or furnaces of different kinds by what is termed the "spraying method," to provide suitable convenient devices for regulating and controlling the flow of the different elements of the fuel to the furnace and indicate the quantity of the same, and utilizing superheated steam to spray the oil and mix the inflowing air with the sprayed oil against a deflector in the furnace for the purpose of scattering the spray over the furnace; and my invention further consists in the constructions and combinations and arrangements of parts, as hereinafter specified, and pointed out in the claims.

In the accompanying drawings, which are made a part hereof and on which similar reference characters indicate similar parts, Figure 1 is a sectional view, parts in elevation, of my improved burner. Fig. 2 is a front elevation of the collar, into which is entered the device in its application to a furnace. Fig. 3 is a detached view showing the regulating and indicating device for the oil-supply. Fig. 4 is a similar view to Fig. 3, showing the steam regulator and indicator; and Fig. 5 is a modified view of my invention.

In said drawings, A represents a tube forming the oil-chamber, which tube is entered into a hole e in the sleeve C, which sleeve is built into the front of the furnace and is open to the air except to the inner projecting portion having the opening c. The tube A is internally bored at a to form a valve-seat

for the tapered point b of the inner tube B, the tapered point b serving as a valve for regulating the oil-supply to the furnace. An 55 inner circular ring a³ is formed in tube A, constituting the back wall of the oil chamber or tube A. A packing-nut E, provided with screw-threads, is entered into the screw-threaded portion of a² of the expanded portion A'. Said nut E is screwed up against the circular ring or flange a³ and surrounds the inner tube B. Suitable packing is interposed between said ring and nut, forming a 60 tight joint around the tube B to prevent escape of oil from chamber A. Oil is supplied to the chamber or tube A by pipe H, which is entered into said oil-tube by screw-threads and is connected with a suitable source of 65 oil-supply.

The inner tube B constitutes the steam-pipe. A tapered end forming a valve for the oil-supply is provided on said tube, as described. At a point near the outer end of tube B and within the enlarged portion A' of chamber A is provided a collar F, which surrounds the tube B and has a screw f passing through the collar and into said tube, by which the collar is rigidly attached to the tube, thus forming a shoulder or bearing against which the sleeve portion g' of the oil regulator and indicator G has contact. Screw-threads on the outer circumference of sleeve portion g' engage with corresponding screw-threads a' of the expanded portion A', and by turning 70 lever G, which loosely surrounds tube B, to the right sleeve portion g', bearing against the rigid collar F, forces said collar, and with it the connected tube B, toward the end of the burner, thus closing or partly closing the 75 space or valve a in chamber A and cutting off the oil-supply. At its rear or outer end tube B is provided with screw-threads b', by which said tube is rigidly connected to tubular portion D², said portion D² forming a 80 shoulder or bearing against which the rear side of the regulator contacts. As the lever 85 G is turned to the left the tube B is withdrawn by the action of said regulator bearing on the end portion of sleeve D², thus 90 opening or partly opening the oil-valve.

The expanded portion A' is provided with a flat circular side upon which is marked a graduated scale G'. The lever or regulator

G is provided with a pointer g in suitable position to register with the scale, and when lever G is moved to operate the oil-valve the pointer, having been adjusted in proper relation, will indicate on the graduated scale the distance the valve b is moved from or toward its seat, thus indicating the quantity or flow of oil to the burner.

The steam-supply is controlled by rod D, 10 provided with a tapered portion and needle-point d at its inner end. Said rod is inclosed within the tube B and has a screw-threaded portion engaging the solid portion of piece D². An operating-lever D' is rigidly attached to 15 the outer end of rod D. A needle or pointer d' is adjusted in proper relation to the indicating-marks on the flat disk d², which is formed upon the end of portion D². In operation when lever D' is turned to either the 20 right or left by its screw engagement with the threads on D² the rod is entered or withdrawn in the tube B and by its tapered point or valve d closes or opens the tapered valve-seat b in tube B, thus shutting off or permitting the entrance of steam to the furnace. 25 Steam from the boiler in a superheated state is supplied through pipe I, which is of a curved or arched form and flexible to allow for the backward and forward movement of tube B, as explained. Said pipe I is connected, through a union-joint and pipe J, to the superheater L, which superheater is placed in suitable position in the furnace. The superheater is formed with a conical 35 point L' for breaking up and scattering the oil, thus rendering the oil which is sprayed against it in better condition for burning.

The sleeve or collar C is provided with apertures c' for retaining pipes I and J and for 40 retaining main steam-pipe K, which is connected to the boiler. With the exception of the bosses, in which are provided the apertures c and c', the sleeve C is entirely open to the air, and air is thus admitted to the 45 furnace through the collar for combustion.

In the modification shown in Fig. 5 the large tube 1 has an inlet 2 for steam, and the smaller inner tube 3 has inlet 4 for oil, the introduction of the elements being reversed

50 from the case with the form shown in Fig. 1. The steam-supply is regulated and indicated

by the device 1^a, and the oil-supply is controlled and indicated by the device 3^a, as will readily be understood.

Instead of using steam as a medium for 55 spraying the oil I may use compressed air or other suitable means.

What I claim is—

1. In a liquid-fuel burner, the outer and inner tubes fashioned to form a valve as described, the inner tube having a valve-seat and inclosing a valve-rod adapted to fit said seat, one of said tubes being movable; a superheater, located in a furnace, and having flexible steam connection to said movable 65 tube, and suitable regulating means for said valves, substantially as described.

2. An injector consisting essentially of two tubes one inclosing the other and fashioned to form a valve as described, a lever provided 70 with a sleeve portion having screw connection with the oil-tube and surrounding the steam-tube and adapted to move said steam-tube, fixed front and rear bearing-rings on the inner tube for said sleeve portion, and a 75 valve-rod having suitable regulating means within the inner tube adapted to form a valve in one end thereof, combined with a flexible steam-pipe connecting the steam-tube to the furnace, substantially as described. 8c

3. In a liquid-fuel burner, the movable and fixed tubes forming a valve as described, the movable tube inclosing a valve-rod adapted to fit a seat in said tube, combined with a superheater located in a furnace, and a flexible 85 steam-supply pipe from the superheater to said movable tube, all combined substantially as described.

4. In a device of the character described, a conical-shaped superheater, substantially as 90 shown, located in a furnace, an oil-injector having a movable tube as described, and flexible steam connection from said movable tube to said superheater, all combined substantially as described.

In testimony whereof I affix my signature in presence of two witnesses.

ROBERT G. KIRKWOOD.
